COMBINED BRUSH AND COMB OR THE LIKE

Eric Dent, 21 Dale Ave., Toronto, Ontario, Canada

Filed June 12, 1961, Ser. No. 65,548

Term of patent 14 years

(Cl. D86—10)

FIG. 1 is a perspective view of the combined brush and comb;

FIG. 2 is a side view thereof;

FIG. 3 is a bottom view of the same; and

FIG. 4 is a top view of the combined brush and comb.

The essential features of the design reside in the portions shown in full lines on the drawing and consists primarily in the provision of a plurality of broad based, flat, tapering teeth of increasing width at the forward end in combination with bristle and toothed structure, all as shown.

I claim:

The ornamental design for a combined brush and comb or the like, as shown and described.
